UNITED STATES PATENT OFFICE.

WILLIAM JAMES WEST, OF ALDER, WASHINGTON.

COMBINATION TOOL.

Application filed March 26, 1927. Serial No. 178,761.

This invention relates to combination tools and particularly to a tool designed for the purpose of constructing and repairing wire fencing.

5 The general object of the invention is to provide a tool which shall combine in one a hammer, wire cutters, pliers, wire stretchers, and a staple extractor.

10 A further object of the invention is to provide a tool of this character which has certain parts thereon peculiarly adapted for the purpose of removing old staples from posts so as to permit the taking up of slack and which also is so constructed as to permit 15 the slack to be readily taken up and the wire re-stapled.

15 A still further object is to provide a device of this character which is very simple, compact, and which has been found to be 20 thoroughly effective in practice.

My invention is illustrated in the accompanying drawings wherein:—

Fig. 1 is a side elevation of my improved combination tool;

25 Fig. 2 is a side elevation of one of the jaws and the corresponding head;

Fig. 3 is a section on the line 3—3 of Fig. 1;

30 Fig. 4 is a section on the line 4—4 of Fig. 1;

Fig. 5 is a section on the line 5—5 of Fig. 1; and

Fig. 6 is a face elevation of the jaw 15.

Referring to these drawings it will be seen that my improved tool consists of two crossed shanks 10 and 11, each shank having a handle 12, and each shank having a circular portion 13 less in thickness than the thickness of the shank so that these circular

40 portions will abut against each other. These circular portions are held in rotative engagement by means of a pivot bolt or pin 14. Extending from the head 13 of the handle 11 is a radially projecting jaw 15 which

45 has an approximately straight inner face 16 preferably serrated and a rounded outer face 17. This outer face is not only rounded longitudinally to the extremity of the jaw 15 but is rounded transversely so that the 50 jaw is more or less circular in cross-section.

On the head 13 of the shank 10 there is formed the hammer head 18 and the rearwardly extending jaw 19 which confronts the jaw 15 and coacts therewith. The inner 55 face of the jaw 19 is straight for the greater

portion of its length so as to fit flat against and extend parallel with the face 16 of the jaw 15 and the inner face of the jaw 19 is preferably serrated. The jaw 19 is longer than the jaw 16 and the jaw is tapered towards its 60 extremity so that the jaw 19 terminates in a curved and pointed portion 20 projecting beyond the extremity of the jaw 15. The jaw 19 is also transversely curved or rounded in cross-section. The heads of the shanks 65 10 and 11 are formed with coacting wire cutting blades 21 and 22 having the form of the usual wire cutters.

The tool, as described, may be used as a wrench, as a pair of pliers, as a hammer, as 70 a wire cutter, as a staple extractor, and as a wire tightener. The use of this device as a hammer, a wrench, and a wire cutter will be obvious and requires no special explanation, but the particular value of this tool re-

75 sides in its usefulness in extracting old staples from fence posts and tightening slack wires thereon. The prolonged portion 20 of the jaw 19 constitutes the staple extractor.

The jaws of the usual staple pullers are of 80 very hard steel and inasmuch as these staple pullers have to bite upon the staple, in order to pull it, they usually bite into the fence wire and the hard pressure which has

85 to be exerted on the jaws and the slipping of the puller acts oftentimes to cut the fence wire or partially cut it, thereby causing

90 breaking of the wire when the wire is stretched again. In the use of my device, where the staple is hard to draw out, the sharp point 20 of the upper jaw is driven beneath the staple by blows on the hammer

95 head 18 and the point 20 therefor forms a pry when so driven under the wire and the staple. The jaws are left open and the jaw 95

100 15 may be closed upon the staple after it has been loosened and then the staple withdrawn by the leverage action of the handles without losing the staple as the old staple will be clamped between the jaws 15 and 19.

105 In using my device as a stretcher, the two jaws having notches or serrations upon the inner faces, grip the wire tightly and the jaws being rounded and tapering to a point, make it easy to take up the slack. In doing 105 this work, the staple in the post nearest to the center of the slack should be taken out and the wire placed between the jaws directly opposite the post. Under these circumstances, the rounded jaws will form a spool 110

upon which the wire may be wound if the tool be turned either to the right or left. This winding of the wire upon these jaws takes up the slack and when the wire is 5 tight, staples are used to fasten the wire firmly to the post on each side of the jaws. Inasmuch as the jaws run to a sharp point, the wire which has been wound upon the jaws may be easily slipped from the jaws, which 10 would not be the case were the jaws not rounded and tapering. Furthermore, if the jaws were not rounded, it would not be an easy matter to turn the jaws and the wire would be liable to bend over the corners of 15 the jaws and weaken at this point. Inasmuch as the jaws form the center around which the wire is wrapped, great leverage is secured and slack in old wires may be readily taken up.

20 I claim:—

1. A tool of the character described including crossed shanks having handles and pivoted to each other, one of the shanks being provided with an outwardly projecting 25 jaw flat on its inner face, and the other shank being formed with an outwardly projecting jaw having a flat inner face bearing against the first-named jaw but projecting longitudinally beyond the same and having 30 a pointed rounded extremity, the opposite end of the jaw being formed with a head whereby the rounded extremity may be driven beneath a staple for the purpose of extraction.

35 2. A tool of the character described including crossed shanks having handles, the shanks being pivoted to each other, each shank having a projecting jaw, the jaws extending parallel to each other and having 40 flat inner contacting faces, each jaw being transversely rounded from the flat inner face and being longitudinally tapered, the outer jaw projecting longitudinally beyond the inner jaw and tapering to form a point which 45 may be forced beneath a staple, the opposite end of the outer jaw having a hammer head

whereby to permit the outer jaw to be driven beneath a staple.

3. A tool of the character described including two shanks having handles and circular heads, the heads fitting against each other and being pivoted to each other, one of said heads carrying a radially projecting jaw having a flat inner face and being transversely rounded and tapering towards its 50 outer end, the other head being formed with a jaw extending substantially parallel to the first-named jaw when the jaws are closed and having a flat contacting face, the last-named jaw being longer than the first-named jaw 55 and tapered longitudinally to a point and being transversely rounded, said second-named jaw being formed to provide a hammer head at the end remote from the point whereby to permit the pointed end to be 60 driven beneath a staple.

4. A tool of the character described including two shanks having handles and circular heads, the heads fitting against each other and being pivoted to each other, one of the 70 said heads carrying a radially projecting jaw having a flat inner face and being transversely rounded and tapering toward its outer end, the other head being formed with a jaw extending substantially parallel to the 75 first-named jaw when the jaws are closed and having a flat contacting face, the last-named jaw being longer than the first-named jaw and tapered longitudinally to a point and being transversely rounded, said second-named jaw being formed to provide a hammer head at the end remote from the point whereby to permit the pointed end to be 80 driven beneath a staple, the two jaws being 85 so formed as to be capable of grasping a staple after the second-named jaw has been forced beneath the staple and the staple loosened from the post.

In testimony whereof I hereunto affix my signature.

WILLIAM JAMES WEST.
